BUMPER ELEMENT FOR MOUNTING UNDER- NEATH CONVEYOR BELTS OR THE LIKE

Sven-Erik Dyrup, Oxie, Sweden, assignor to
Trelleborgs Gummifabriks AB

Filed Feb. 15, 1974, Ser. No. 442,949

Claims priority, application Sweden Aug. 17, 1973

Term of patent 14 years

Int. Cl. D12—05

U.S. Cl. D55—1 C

FIG. 1

FIG. 2

FIG. 3

FIG. 4

FIG. 1 is a bottom plan view of one end of a bumper element for mounting underneath conveyor belts or the like, shown fragmentarily for convenience of illustration showing my new design;

FIG. 2 is a top plan view of said one end of the bumper element of FIG. 1;

FIG. 3 is a side elevational view of said one end of the bumper element of FIG. 1;

FIG. 4 is an end elevational view of the bumper element of FIG. 1 and shows the bumper element from the left with regard to FIG. 1;

FIG. 5 is a perspective view showing the bumper element for mounting underneath conveyor belts or the like from the top side thereof; and,

FIG. 6 is a perspective view showing the bumper element for mounting underneath conveyor belts or the like from the bottom side thereof.

I claim:

The ornamental design for a bumper element for mounting underneath conveyor belts or the like, as shown and described.
